UNITED STATES PATENT OFFICE.

CHARLES W. GILES, OF ATTLEBORO, MASSACHUSETTS.

RAILWAY CROSS-TIE.

1,089,048.

Specification of Letters Patent.

Patented Mar. 3, 1914.

Application filed February 24, 1913. Serial No. 750,196.

To all whom it may concern:

Be it known that I, CHARLES W. GILES, a citizen of the United States, and resident of Attleboro, in the county of Bristol and State 5 of Massachusetts, have invented certain new and useful Improvements in Railway Cross-Ties, of which the following is a specification.

This invention relates to railway cross ties 10 and the operating of signal apparatus by an electrical circuit completed through said tie, and has for its object to provide a railway tie of composite construction which is electrically connected to a danger signaling device whereby if the rails spread a predetermined amount the electrical circuit will be closed and the signal set to danger which will cause the investigation of the condition 15 of the tracks.

20 A further object of the invention is to provide a metallic railway tie member having rail supporting blocks of non-electric-conducting material mounted therein said tie member being provided with block retaining members or pockets having contacting portions located on the outside of each rail which members serve a double purpose first to retain the blocks in position in the tie member, and second, they serve to complete an electric circuit to set the signal to danger when the rails spread sufficiently to engage them.

A further object of the invention is to form the tie member of metal bent or shaped into an angular form having a base and one 25 side wall whereby this member is adapted to receive short blocks of non-electric-conducting material for supporting the rails, the rails being spiked, screwed or otherwise secured to the blocks whereby the natural 30 tendency of the rail movement, which is in the direction of the current of traffic, naturally crowds the blocks up against one wall of the tie which wall is primarily constructed for supporting the block against this 35 thrust.

With these and other objects in view, the invention consists of certain novel features of construction, as will be more fully described and particularly pointed out in the 40 appended claims.

Of the accompanying drawings: Figure 1— is a diagrammatic view illustrating a railway block signal apparatus employing my improved railway tie so that if the rails 45 spread at any point in the block the signals will be set to danger. Fig. 2— illustrates a

danger signal operatively connected to the tie itself whereby a spreading of the rails will close the circuit and set the signal to danger. Fig. 3— is a perspective view 60 illustrating the general construction of my improved composite rail showing the pockets for retaining the wooden blocks. Fig. 4— is a section on line 4—4 of Fig. 3 showing the rail mounted on the block of non-conducting material. Fig. 5— is a detail on line 5—5 of Fig. 3 showing my improved means for locking the block in the tie member. Fig. 6— is a detail of the key or strap employed for locking the block. 70

Referring to the drawings, 10 designates the tie member which is preferably constructed of sheet metal rolled into a right angle form providing a base portion 11 and a side wall 12. This tie member is provided 75 at either end with a pocket for the reception of the cushion or non-electric-conducting block hereinafter described and the pocket is preferably constructed by providing a pair of arms 13 and 14 at either end formed integral with the upper edge of the side wall 12 said arms being horizontally disposed and extending across the tie, each pair of arms being connected together by the member 25 which extends downward and is provided 80 with fingers 26 extending through corresponding holes 27 in the base plate, see Figs. 3 and 5, said fingers being bent back beneath said base plate firmly securing these arms in position. In order to close the outer end of 85 each of these block receiving pockets I have provided an end wall portion 28 which is turned downward, see Fig. 4, and provided at its lower edge with fingers 29 which extend through corresponding apertures 30, 90 said fingers being bent outward to lock this edge to the base plate 10.

In order to close the inner ends of these pockets I have provided a key or angle member 15, the same having an outwardly 100 turned lip 16 adapted to extend through a corresponding aperture 17 in the base plate and then extend up and back as at 18 over the upper edge of the arm 14 where it may be secured in position by means of the nail 105 or screw 19. The edges of these arms 13 and 14 are notched or cut away as at 20, see Fig. 3, so as to prevent the spike or lag screw 31 which secures the rail to the block from coming in contact therewith to short 110 circuit the same. The edges of the vertical walls 12 and 25 between these arms is cut

away as at 21, see Figs. 3 and 4, so that the rail in extending over the block between the arms, while in normal position, cannot come in contact with any of the metal parts of the tie member.

5 In order to provide a properly cushioned bearing for the rails, I insert into the pocket portions of this tie member at either end beneath the rails, a block 22 of wood, vulcanized fiber or other suitable non-electrical conducting material and to these blocks I attach the rails 23, either by spikes, lag-screws, or otherwise, see Fig. 4, and by passing the key or strap 15 through the slot 17 and attaching the upper end 18 to the arm 13 the blocks are securely locked in position in their respective pockets. By this construction it will be seen that a very small portion of the wood, as compared to the ordinary wooden tie, is employed in my present construction of composite tie, so that when one of these blocks decays or becomes defective it is not necessary to throw away the whole tie, but simply remove the defective block and replace it with a fresh one.

25 I do not wish to be restricted to forming the arms 13 and 14 integral with the edge of the side wall 12 as it may be formed independent thereof and connected thereto by any suitable means to form and complete the pocket for receiving and retaining the rail supporting blocks.

30 By constructing my improved tie member of angle iron having but one side wall I reduce the weight and cost of constructing the same to the minimum as one wall only is really needed and that is set to form an abutment to take the strain of the blocks which have a tendency only to move in the direction of the current of greatest traffic. Both the side wall and base portion of this tie member between the rails may be cut away if desired to lighten its construction, and the said base and side wall may be made 45 of a stock sufficiently heavy to stand for years, particularly when the same is galvanized or otherwise treated to protect it from the deteriorating action of the elements.

35 In some cases it is proposed to electrically connect sections of the rails 23 into what is known as blocks that is, different sections of the road will be electrically connected in such a way that when a train enters the block it sets the signals behind it to danger to prevent the next following train from entering this block until the first train has passed out and upon leaving the block the signal is cleared. But if for any reason the rails on a tie of my improved construction should 40 spread, the circuit will at once be completed through the metallic tie thereby setting the signal to danger preventing the train from entering the block until investigation has been made. The operation of the block signal through this tie may be entirely inde-

pendent of its action by the travel of the car and having once been set by the spreading of the rails could not be restored to safety until the rails had been removed from electric contact with the tie.

70 It is found in practice that a large percentage of the railroad accidents are caused by spreading of the rails. A slight spread which would cause one of the rails to come in contact with one of the metal arms, would not be sufficient to derail a train, but twice that amount which would bring the opposite rail into contact with the opposite outer metal arm would be considered a dangerous spread nearly sufficient to derail a train and 75 by my improved construction of cross tie such a spread would complete the circuit through the tie and set the signal to danger.

80 I do not wish to restrict the use of my improved tie to a block signaling system to 85 work in combination with the regular danger signals as these ties may be wired up to operate independent signals and so indicate the spreading of the rails by an independent electrically operated system.

90 I claim:

1. In a railway block signal apparatus, the combination with an electrically operable danger signal, of a railroad tie of electrical conducting material having supporting members for the rails of insulating material, and means connected to the tie whereby said rails are automatically connected electrically through said conducting tie to set the signal to danger when the rails become moved a predetermined distance from their normal position.

100 2. In a railway signal apparatus, the combination with an electrically operable danger signal, of a railroad tie of electrical conducting material having supporting members for the rails of insulating material, and means connected to the tie whereby said rails are automatically connected electrically through the conducting tie to set the signal to danger when the rails become moved laterally a predetermined distance from their normal position.

110 3. In a railway signal apparatus, the combination with an electrically operable danger signal having a normally open circuit, of a railroad tie of electrical conducting material having supporting members of insulating material for the rails, and a conducting member connected to the tie on the outside of each rail whereby said rails are automatically connected electrically through the tie to close the circuit and set the signal to danger when the rails become moved laterally a predetermined distance from their 120 normal position.

125 4. In a railway signal apparatus, the combination with an electrically operable danger signal, of a metal railroad cross tie having supporting members for the rails of electrici- 130

cally insulating material, and means whereby the signal is set to danger when the rails become spread and both come in contact with the metal of the tie.

5. In a railway signal apparatus, the combination with an electrically operable danger signal, of a metal railroad cross tie having pockets, supporting members for the rail of electrically insulating material retained in said pockets, and means whereby the signal is set to danger when the rails become spread and both come in contact with the metal of the tie.
6. In a railway signal system, the combination with an electrically operable danger signal having a normally open circuit, of a railway tie member formed of angle iron

having a base and one side wall, rail carrying blocks of non-conducting material in said member, arms extending from said wall 20 out over said blocks to assist in retaining them in position, said arms being set on each side of each rail and spaced apart a distance greater than the width of the rail set between them, whereby a lateral movement of both the rails into contact with said arms completes the circuit and throws the signal to danger.

In testimony whereof I affix my signature in presence of two witnesses.

CHARLES W. GILES.
